Primary Examiner — Leanne Was-Englehart*Assistant Examiner* — Justin A Johnson(74) *Attorney, Agent, or Firm* — Olive Law Group, PLLC(57) **CLAIM**

The ornamental design for a bicycle helmet, as shown and described.

DESCRIPTION

FIG. 1 is a top, front and left side perspective view of a bicycle helmet, showing my new design;
FIG. 2 is a bottom, rear and right side perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines shown in the drawings depict the portions of the bicycle helmet that form no part of the claimed design.

1 Claim, 8 Drawing Sheets(56)
